UNITED STATES PATENT OFFICE.

FRANK G. HOLMES, OF TRENTON, NEW JERSEY, ASSIGNOR TO LENOX INCORPORATED,
OF TRENTON, NEW JERSEY.

DESIGN FOR A PLATE OR SIMILAR ARTICLE.

Application filed October 10, 1924. Serial No. 11,017. Term of patent 14 years.

To all whom it may concern:

Be it known that I, FRANK G. HOLMES, a citizen of the United States, residing in Trenton, in the county of Mercer and State of New Jersey, have invented a new, original, and ornamental Design for a Plate or Similar Article, of which the following is a specification, reference being had to the

accompanying drawing, forming part thereof.

The figure is a plan view of a plate showing my new design.

I claim:—

The ornamental design for a plate or similar article, as shown.

FRANK G. HOLMES.
